UNITED STATES PATENT OFFICE.

ORSON R. VAN SICKLE, OF TOLEDO, OHIO.

RAIL TIE AND CLAMP.

1,381,145.

Specification of Letters Patent. Patented June 14, 1921.

Application filed March 14, 1921. Serial No. 452,052.

To all whom it may concern:

Be it known that I, ORSON R. VAN SICKLE, a citizen of the United States, and a resident of Toledo, in the county of Lucas and State of Ohio, have made an Invention Appertaining to Rail Tie and Clamp; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to railway ties and rail clamping means therefor, and particularly to those of the metallic type.

The object of the invention is the provision of a strong and durable tie of the class 20 described, which is easy, cheap and simple to manufacture and is provided with simple and efficient means for attaching a rail thereto.

The invention is fully described in the 25 following specification, and while in its broader aspect it is capable of embodiment in numerous forms, a preferred embodiment thereof is illustrated in the accompanying drawings, in which,—

30 Figure 1 is a perspective view of a tie embodying the invention, with a part broken away and with a rail clamped thereto. Fig. 2 is a cross-section on the line 2—2 in Fig. 1, and Fig. 3 is a section on the line 3—3 in 35 Fig. 1.

Referring to the drawings, 1 designates a tie embodying the invention, and 2 a rail mounted thereon. The tie is of comparatively thin metal construction, being preferentially stamped from a heavy grade of sheet metal and has the transversely spaced top rail supporting ledges or portions 3, 3 extending throughout its length and integrally connected at their inner edges by a V-shaped 45 longitudinally extending trough portion 4. Each top portion 3 is provided at its outer edge with a depending flange 5, which preferably projects outward and downward on an incline and is of less depth than the 50 trough portion 3. This construction provides a tie which is especially strong and durable and is at the same time light and inexpensive, and facilitates ballasting, the spaces between the trough portion 4 and 55 side flanges 5 being provided for such purpose.

At each point of intended crossing of the tie by a rail, a pair of wings or lips 6 are provided in opposed relation at the top edges of the trough 4 so that they project inward over the trough, one toward the other, in the plane of the top portions 3, 3. These wings, if the tie is of stamped sheet metal construction, are struck up from the respective side walls of the trough and in width are substantially the same as the rail base.

A clamping means coöperates with the wings 6 to firmly hold a rail base to the tie, and in its present embodiment comprises a base member 7, top member 8 and uniting bolt 9. The base member 7 extends under a pair of wings 6, lengthwise of the tie and has one end turned up and inward in hooked form to engage over an edge of the rail base. The top member 8 is clamped to the other end of the base member 7 at a side of the rail base and has its inner edge portion extending upward and inward to engage over the adjacent edge of the rail base. The members 7 and 8 are secured together in rail clamping relation by the bolt 9.

I wish it understood that my tie may be either stamped, rolled or cast, and is not limited to any specific construction, arrangement or form of the parts, as it is capable of numerous modifications and changes without departing from the spirit of the claims.

Having thus described my invention, what I claim as new and desire to secure by Letters Patent, is,—

1. A railway tie having transversely spaced rail supporting portions, a depressed V-portion connecting the rail supporting portions, flanges depending from the outer edges of the rail supporting portions, and a wing projecting over the V-portion from the inner edge of one of the top portions.

2. A railway tie having transversely spaced rail supporting portions, a depressed V-portion connecting the rail supporting portions, flanges depending from the outer edges of the rail supporting portions, and opposed wings projecting inward over the V-portion from the inner edges of the rail supporting portions in the plane therewith.

3. A railway tie of sheet metal construction having transversely spaced rail supporting portions, a connecting interposed trough portion, side flanges depending from the outer edges of the top portions, and opposed wings projecting inward from the inner edges of the top portions in position to

underlie a crossing rail, said wings being slit from the side walls of the trough portion and bent upward therefrom.

4. In combination, a rail tie having spaced rail supporting portions and an interposed trough portion, a wing projecting from one of the top portions over the trough portion, a rail crossing the tie over the wing, and clamping means extending under the wing and having clamping engagement with the rail base.

5. In combination, a tie of sheet metal construction having transversely spaced rail

supporting portions, side depending portions and an intermediate connecting trough portion, wings projecting in opposed relation from the edges of the top portions over the trough portion, a rail crossing the tie over the wings, and clamping means for extending under the wings and coöperating therewith to engage and clamp the rail base to the tie.

In testimony whereof, I have hereunto signed my name to this specification.

ORSON R. VAN SICKLE.
